CLEANING DEVICE.

970,466.

Specification of Letters Patent. Patented Sept. 20, 1910.

Application filed January 12, 1907. Serial No. 352,018.

To all whom it may concern:

Be it known that we, GEORGE CLEMENTS and JAMES M. HOSTLER, citizens of the United States, residing at Chicago, in the 5 county of Cook and State of Illinois, have invented a certain new and useful Improvement in Cleaning Devices, of which the following is a specification.

Our invention relates to cleaning devices 10 and is illustrated in the accompanying drawing which is to be taken as in an important sense diagrammatic.

A is the interior of a room, B a rug on the floor thereof, C a sofa, let us say plush covered, in the room.

D is the body portion of a brush and D¹ the bristles. Associated with the same is a metallic part consisting of the hollow body D² and the downwardly depending 20 nipples D³ D⁸, which pass through the body, and the upwardly projecting inclined portion D⁴ to which the hollow tubular handle D⁵ is attached. From this handle leads the hose D⁶ to the wagon E. This hose may lead 25 to a fixed stand-pipe D⁷, which is connected by a further length of the hose D⁶ with the wagon.

F is another cleaning device, in this case the well known suction device, associated 30 with the handle F¹, hose F², stand-pipe F³ and hose F⁴ which leads to the wagon. G is a fluid cleaner tank situated on the wagon F and provided with the filling device herein shown as a funnel G¹. The tank G is 35 connected to the pressure tank G⁴ by the connection G³ controlled by the valve G². G⁵ is a pipe which leads from near the bottom of the fluid cleaner tank to the hose D⁶. The hose F⁴ leads to the suction pump J.

40 These several parts, as previously stated, are shown diagrammatically and we do not intend to restrict our invention to the precise form, arrangements, sizes or proportions of the several elements. We have only shown a 45 part of the mechanism on the wagon, though the other parts will be easily understood. Moreover, neither of these stand-pipes is necessary as a permanent fixture as the hose itself could be led directly from the wagon 50 to the room where the work is to be done.

The use and operation of our invention are as follows: In the cleaning of many articles of furniture it is highly desirable that a wet cleaning as well as a dry cleaning

process should be carried on. The exhaust 55 system is in effect a dry cleaning system. Associated with the apparatus necessary for carrying it on, we provide our wet cleaning apparatus. This consists of a pressure supply on the wagon, a fluid cleaner storage 60 on the wagon, suitable connections therefrom and a discharge wet cleaning apparatus for actual use. If the tank G be charged with a fluid cleaner, as for instance some kind of liquid soap, by operating the 65 necessary valves pressure can be applied within such tank and to the surface of its contained fluid. This will drive the fluid in regulable quantities up through the various pipe connections to the cleaning brush 70 and if this brush be operated the effect will be to brush or scrub the surface to be cleaned while, at the same time, the brush is supplied with a cleaner fluid. When this process is finished, or the object has been sufficiently scrubbed, dry cleaning apparatus 75 may be employed to withdraw such cleaner fluid together with the dirt and dust incorporated with it. In such a dry cleaning apparatus the exhaust is usually made through 80 some kind of a filtering receptacle and we have omitted showing this because it is unnecessary for illustrating the broad principle.

We have shown the wagon with a good 85 deal of the mechanism removed as it is unnecessary here to illustrate it. We show only those portions of the apparatus on the wagon which are directly connected with the cleaning device.

90 We claim:

A cleaning device comprising a portable frame or body with a cleaner fluid storage tank thereon, a pressure supplying device thereon, and a suction device thereon, a 95 cleaning brush, a flexible pipe leading from the fluid cleaner tank to the cleaning brush, a suction cleaner device and a pipe leading therefrom to the suction device on the wagon, and suitable controlling valves 100 whereby the suction and brush devices may be operated simultaneously or successively.

GEORGE CLEMENTS.
JAMES M. HOSTLER.
